UNITED STATES PATENT OFFICE

EDWIN JONES, OF EAST CLEVELAND, OHIO

UNCOUPLING DEVICE FOR RAILWAY CARS

Application filed May 28, 1927. Serial No. 195,055.

This invention relates to uncoupling devices for railway cars and more particularly to two piece uncoupling devices. An object of the invention is to form an uncoupling device which allows enough end play to prevent distortion or binding thereof if the draft gear has excessive slack, which may be due to wear, broken draw springs, bent followers, etc. This result is according to the invention obtained by the size and form of the crank shaft arm and loop, the design of which permits sufficient travel of the connection link to avoid any destruction or distortion thereof.

An important object of the invention is to form an uncoupling device which will positively prevent the fouling of the locking pin or prevent said pin from dropping freely when the locking pin is raised to release position, ready to make the next coupling, which is usually caused by some part of the connection slipping or binding in the eye of the locking pin preventing the pin from dropping in place when the knuckle is forced back in making the coupling. This defect makes it necessary for train men to go in between the cars and correct the trouble by freeing the lock pin so it will drop in place before the coupling can be made and many men are injured by having to go in between the cars to overcome this trouble. This trouble is overcome in my invention by the design of the connection, its guides, and the crank arm loops of the uncoupling lever, which positively prevents the connection from tipping to one side or the other and binding in the eye of the locking pin, when the locking pin is raised to release position.

Another object of the invention is to provide a two piece uncoupling device which can be applied or removed from the knuckle locking pin and the crank shaft or uncoupling lever, freely and without the use of any tools, and without having to remove the uncoupling lever from the car or from the brackets which hold the lever in place, but with which an accidental or self loosening of the connection is practically impossible. Such result is obtained by the specific form and design of the crank shaft arm and loop and connection link, which specific form and arrange-

ment of parts will more readily be understood by the following description and the drawings forming part hereof, and which drawings show in:

Fig. 1, a perspective view of a coupler on a car with my improved uncoupling device; Fig. 2, a front view of the connecting link; Fig. 2^a and Fig. 3, side views of Fig. 2; Fig. 4 a front view of the crank shaft arm and loop; Fig. 5 a side view of Fig. 4; Figs. 6, 7 and 8 are front, side and top views of the uncoupling device in locked position; Figs. 9 and 10 side views of the uncoupling device with knuckle lock in released position, with the connection link arranged in different position in the crank shaft loop; Figs. 11 and 12 are side and front views of the uncoupling device with the locking pin of the coupler partly raised for disconnecting or applying connection link from or to crank shaft arm and loop. Fig. 13 is a front view of a modified connecting link.

As shown crank shaft 2 is in the usual manner supported by brackets 3 on the end of the car body 4, slightly above the car coupler of standard type in which the knuckle is provided with a knuckle lock within the coupler head, and the vertically movable lock release pin 5 is provided as usual. This pin which has to be raised in order to unlock the knuckle, is slidably connected by a special link member 7 to the front end of crank shaft 2 having an integral crank arm 6. Crank arm 6 as shown in Figs. 4 and 5 is provided at its end with two loops, a guiding loop 8 and a disconnecting loop 9 and this latter is of nearly triangular shape for a purpose later to be described.

Link member 7 is provided with an upper yoke member 10 and with a lower depending integral hook or arm 11. The yoke 10 has prongs 12 and 14 standing side by side and connected by a cross piece 16, the rod being bent to form both prongs and extending downwardly and bent to form the lower cross arm 11 parallel to the connection 16 between the prongs 12 and 14. The end of arm 11 is also bent up slightly to form a bill 15 inclined upwardly with respect to the axis of the arm 11 (see Figs. 6 and 7). Both prongs of the

yoke are bent in loops to give the prongs a certain width which prohibits turning and disconnecting of the yoke when connected to crank shaft loop 8, see Figs. 6, 7 and 8.

5 As the width of the prongs is such that they cannot accidentally pass through the loops 8 or 9 of the crank shaft arm the device is safe against accidental uncoupling. When link member 10 is raised to a certain position—that is when the locking pin 5 is about half way up between locking and unlocking position as indicated in Fig. 11, by "a" (the unlocked position (see Figs. 9 and 10) being indicated by "b") and the whole link connection is moved into the triangular shaped loop 9, the connection 16 between the two prongs 12 and 14 of link member 10 abuts against the upper inside edge 17 of loop 9 and the lower part 18 of prong 12 is 10 slightly above the lower edge 19 of loop 9. In this position, a tilting and slight turning of link member 10 and sliding of arm 11 in the hole in the head of pin 5 causes partial disengagement between link member 10 and loop 9. To permit further turning and an 15 entire disengagement of link member 10 from the crank shaft loop, arm 11 is slightly bent as at 15 and the desired disconnection or connection can readily be made without any distortion or bending of other parts, the action 20 being illustrated in Figs. 11 and 12.

This link construction is so arranged, as 25 shown in Fig. 7, that it is absolutely impossible to disengage the parts when locking pin is in a locked position, as in this position the prongs 12 and 14 at opposite sides of the loops 8 and 9 prevent any tilting or turning of the link member 10.

When the locking pin is in a released position, the natural position of the link member 40 10 is in loop 8, but should link member 10 accidentally slip or be placed into loop 9 such a position would not be sufficient for self disengagement of the link member from the crank shaft arm, as the weight of the 45 crank shaft arm 6 pressing downwardly upon the connection 16 of prongs 12 and 14 positively forces the connection 16 into a locking position in loop 9. A disengagement of link 50 10 is only possible in two positions, that is, when locking pin 5 has to be raised into a position about half way between its two limit positions (locked or unlocked) as shown in Figs. 11 and 12, and when locking pin 55 is raised to a full release position as shown in Figs. 9 and 10 and the crank shaft arm 6 raised to a certain height, link member 10 can then be adjusted and removed or applied as shown in Figs. 11 and 12.

60 Fig. 13 shows a modified form of the prongs of the connecting member, the prongs 12^a and 14^a being parallel instead of slightly "canted" as in the other figures. It may be 65 stated that the forms of the prongs may be changed without departing from the scope

of the invention, which comprises a two part connection of uncoupling devices adapted to be operated or disconnected without any violence or distortion but secure against accidental self-release.

70 I claim:

1. An uncoupling device, comprising a crank having an arm with communicating loops at its end, and an upright hanging link having a lower bar adapted for sliding engagement with a coupler locking pin, and having at its upper end a pair of prongs connected by a bar working in the loops, the link being shiftable laterally with respect to the locking pin to permit removal of one of the prongs through one of the loops for disconnecting the link from the crank arm and locking pin.

75 2. An uncoupling device comprising a shaft having a crank arm provided at its free end with upstanding loops one of which is triangular in shape, and a connecting link having its lower cross arm slidably engaging a coupler locking pin, and having at its upper end a pair of prongs between which 80 the loops extend, said prongs being connected by a cross arm working in the loops, the link being shiftable laterally to withdraw one of the prongs through the triangular loop when the coupler locking pin is lifted, and not 85 otherwise.

90 3. An uncoupling device comprising a rock shaft having a crank arm provided with a pair of upstanding communicating loops one of which is disposed at an angle to the other, and a link adapted to slidably engage a coupler lock pin and having a pair of upstanding prongs between which the loops extend, the link being shiftable to permit withdrawal of one of the prongs through one of the loops when the locking pin is raised but 95 otherwise.

100 4. The combination of a crank having an arm provided with two upstanding loops located one in front of the other, and an upright link having a pair of upstanding prongs at opposite sides of said loops, a cross piece connecting said prongs and extending across above the arm, and a lower cross arm connected at one end to one of said prongs and 105 adapted to slidably engage a locking pin, the link being shiftable from one loop to the other to permit disconnection of the link from the arm when the latter is in a lifted position.

110 In testimony whereof, I do affix my signature.

115 EDWIN JONES.
